UNITED STATES PATENT OFFICE

171,934

COFFEE TABLE OR SIMILAR ARTICLE

Abraham Dobbins, Los Angeles, Calif.

Application July 9, 1953, Serial No. 25,862

Term of patent 7 years

(Cl. D33—14)

To all whom it may concern:

Be it known that I, Abraham Dobbins, have invented a new, original, and ornamental Design for a Coffee Table or Similar Article, of which the following is a specification, reference being had to the accompanying drawing, forming a part thereof.

Fig. 1 is a front perspective view of a coffee table or similar article showing my new design;

Fig. 2 is a rear perspective view thereof.

I claim:

The ornamental design for a coffee table or similar article, as shown.
